UNITED STATES PATENT OFFICE.

WASYL ZADOROZNY, OF MEACHAM, SASKATCHEWAN, CANADA, ASSIGNOR OF ONE-HALF TO TONY ZYGIEL, OF HAMILTON, ONTARIO, CANADA.

PADLOCK.

1,308,319.

Specification of Letters Patent.

Patented July 1, 1919.

Application filed March 13, 1919. Serial No. 282,432.

To all whom it may concern:

Be it known that I, WASYL ZADOROZNY, a citizen of Austria, residing at Meacham, Province of Saskatchewan, and Dominion of Canada, have invented certain new and useful Improvements in Padlocks, of which the following is a specification.

This invention relates to improvements in portable locks adapted to engage with a 10 staple or the like whereby a latch may be secured.

The principal object of the invention is to provide a lock of the permutative kind, having a pair of disks adapted to be rotated from the exterior of the lock into definite position, so that the tumbler may engage within sockets formed therein.

A further object is to provide means which prevent the release of the bow of the 20 lock, irrespective of the position of the disks, except that it must be first moved so as to free the coupler.

These and other like objects are attained by the novel construction and combination 25 of parts hereinafter described, and shown in the accompanying drawings, forming a material part of this disclosure, and in which—

Figure 1 is a front elevational view showing a lock made in accordance with the invention.

Fig. 2 is a longitudinal sectional view taken immediately below the cover.

Fig. 3 is a similar view of the same, the 35 interior parts being in different positions, and

Fig. 4 is a transverse sectional view taken on line 4—4 of Fig. 2.

Referring to the drawings, the lock is 40 seen to comprise a body representing two squares, superposed one upon the other, presenting octagonal points 10 and 11, to which the cover 12 is secured by rivets 14, and containing an opening 15, in which the 45 mechanism is disposed.

One of the points or blocks 16 has an inwardly extending stem 17, slideable within a 50 elongated slot 18, formed within the edge of the lock and held in position by a nut 19 screwed upon the end of the stem.

The bow 20 is pivotally engaged within the lock body by the rivet 21 and is of the usual U shaped construction, its inwardly extending end 22, passing through

an opening 23, and having a transverse recess 24, extending inward from its outer surface, with which is engaged the inturned hook-end 25, of a tumbler 26, pivoted upon the pin 27 and normally pressed out of engagement by the bent flat spring 28.

The inner projecting end 30 of the tumbler is engageable within recesses or sockets 32 and 33, formed in the periphery of a pair of disks 34 and 35, journaled to rotate within the casing, the disk 35 being 55 positioned against the lower inner surface of the body 15, and is provided with an extending stem 36, the same passing through the cover plate 12 and provided with a lever arm 37, simulative of the minute hand of a clock, the same being rotatable with reference to a plurality of circular graduations 38, formed upon the exterior of the casing 12, and by which it may be definitely located in an adjusted position. 60

The other disk 34, through which the stem 36 passes, has an extending sleeve 40, secured to which is an arm or lever 41, representing the hour hand of a clock, and also registerable with the graduations 38. Thus 65 by rotating the levers 37 and 41 into a definite position relative to the graduations the recesses 32 and 33 may be brought into registration with the extending arm 30 of the tumbler, so as to permit the same to 70 enter the recesses, whereupon, due to the action of the spring 28, the engaging hook element 25 is removed from the recess 24, permitting the bow of the lock to be raised, normally however, this is prevented in the 75 following manner.

A recess 44 is formed with the tumbler 26, adjacent to the arm 30, and engageable within the recess is the hook detent 45 of a lever 46, pivoted on the pin 47 within the lock casing, the outer end of the lever having pivotally engaged with it a link 48, its outer end pivotally engaged with an extension 49, the same extending from the stem 17, formed with the sliding element 16. 100

From the foregoing it will be seen that a novel and effective form of permutative lock has been disclosed, having in addition to the usual features the sliding block 16, which must be properly manipulated before the bow is released, therefore one merely familiar with the permutative features of the lock, is still unable to release 105

the bow unless he has prior knowledge of the movement necessary to impart to the block 16.

Having thus described my invention, what I claim as new and desire to secure by Letters Patent, is—

In a lock of the class described, the combination with a poly-pointed body, a cover thereover, a chamber formed in said body, 10 and a bow pivotally engaged in said body, the opposite end of said bow to be enterable through an opening formed in the edge thereof, of a pair of disks rotatably engaged in said chamber, said disks having 15 transverse recesses formed in their periphery, an annular row of graduations formed on said cover, elements engaged with said disks extending through said cover, and adapted to be brought into registration with any of the graduations 20

impressed thereon, a tumbler pivoted in said body, said tumbler having a part engageable with said bow, an oppositely disposed extension formed with said tumbler engageable in said recesses when in alignment, a spring adapted to press said extension into engagement, a detent pivoted in said chamber, said detent having a portion engageable with said tumbler, whereby it is held in an operative locked position, a 25 block slidably engaged on said body, said block having a stem extending through a longitudinal slot formed therein and an operative connection between said stem and said detent whereby the detent may be removed from engagement with said tumbler upon actuating said lock.

In testimony whereof I have affixed my signature.

WASYL ZADOROZNY.
